Application May 26, 1955, Serial No. 511,371

6 Claims. (Cl. 3—1.1)

This invention relates to electromechanical control systems and more specifically to voice operated reversible motors for controlling mechanical equipment as for instance prosthetic devices such as the mechanical hand disclosed in U. S. patent application of Charles Giaimo, filed March 23, 1954, Serial No. 418,033.

While the control system in accordance with the invention is of general usefulness, it is particularly effective for prosthetic devices of the type used to actuate an artificial hand or the fingers of the hand in instances when a person through nerve damage or other causes has lost muscular control of the fingers. In the above mentioned application the prosthetic devices were operated by switch mechanisms responsive to air pressure produced by the user through a special mouth piece supported on the chest of the user and disposed in the vicinity of the mouth. This invention overcomes certain of the limitations inherent in pressure operated control and provides a completely safe, easily operated control system for prosthetic devices that will enable a plurality of independent mechanical controls to be selectively actuated, as for instance prosthetic devices for each hand and for individual finger control and to effect more precise hand operation.

Another object of the invention resides in the provision of an improved method and apparatus for selectively controlling a reversible motor and other similar devices in response to the human voice whereby selective operation of several such motors can be attained.

A further object of the invention resides in a new and improved circuit and arrangement of components for selectively controlling a plurality of relays, motors and other mechanical and electromechanical devices in response to the human voice.

A further object of the invention resides in the provision of an improved voice operated prosthetic control.

The above and other objects of the invention will become more apparent from the following description and accompanying drawings forming part of this application.

In the drawings:

Figure 1 is a perspective view of a prosthetic device embodying voice actuated control means in accordance with the invention; and

Figures 2a and 2b illustrate a circuit diagram of voice operated control means in accordance with the invention.

While the invention is useful for a wide variety of applications requiring selective position control of a number of mechanical or electromechanical devices, its advantages and versatility is best expressed by its application as the controlling means for a prosthetic device such as the mechanical hand disclosed in the above mentioned application for U. S. patent. Accordingly the invention will be illustrated and described in connection with such application thereof.

Referring now to Figure 1, a prosthetic device for operating the thumb and first finger of the hand is denoted

2

generally by the numeral 10. This device is coupled by cables 11 to a control mechanism disposed within the box 12. This control mechanism is supplied with power through an extension cord 13 and a plug 14 adapted to be connected to a conventional electric outlet of the type normally used in the home. It will become apparent however that this control device may be battery operated for increased portability. The control 12 is actuated by means of a throat microphone 15 connected by a cable 16 to the box 12 and is preferably supported snugly about the neck of the wearer by means of a strap 17 or other suitable supporting means.

It will be observed, in the illustrated prosthetic device 10, that the thumb of the wearer is held in relatively fixed position with respect to the palm of the hand and that the index finger is moved by means of a series of encircling links or collars toward and away from the thumb by means of pull cables 11, 11. In the operation of this device which will be more completely described in connection with the circuit diagram of Figures 2a and 2b, the user sounds a sustained tone of predetermined frequency and this tone is detected and converted by the microphone 15 to an electric current for actuation of the control device 12. This current is amplified and treated in such a manner that it will actuate a relay within the control 12 which in turn functions to operate an electromechanical device such as a motor connected with the cable 11. In this particular application a motor reversing switch is utilized that functions both as an off-on switch for the motor and a reversing switch. Upon the sound of the first tone by the user the reversing switch will be moved to an "on" position causing the motor to rotate in one direction. The sounding of the tone a second time will cause the switch to rotate to an "off" position. When the tone is sounded again the motor will be energized but this time it will move in a reverse direction. The sounding of the tone a fourth time will move the switch into an "off" position to complete the cycle. In the case where two or more motors are to be selectively controlled to operate, for example, prosthetic devices on each hand, the control unit 12 is arranged to respond to a tone of one frequency for the operation of one motor and to a tone of another frequency for the operation of the second motor. From this it is apparent that a number of motors or control devices may be selectively operated.

The selective control referred to above is shown in Figures 2a and 2b and includes three essential elements for single channel operation, namely, an electronic amplifier 20, a power supply 21 and the electromechanical control 22. Referring first to the power supply there are provided two power transformers 23 and 24 having primary windings 25 and 26, respectively. These windings are connected in parallel and through a switch 27 and fuse 28 to the power cable 13 and plug 14 for connection to a suitable power supply. In order to reduce the effect of line voltage variations on the operation of this apparatus a voltage regulator tube 29 and series resistor 30 are connected across the supply voltage so as to maintain a more nearly constant load as the power demand of the control changes.

The transformer 24 has an adjustable secondary 31 in order to obtain secondary voltages ranging from 0 to about 16 volts. This transformer as will be shown provides the energy for the operation of the control motor forming part of the electromechanical control device 22. By the adjustment of the voltage on the secondary the speed of operation of the motor can be increased or decreased in accordance with the desire of the user. The voltage from the secondary 31 of transformer 24 is rectified by a full wave bridge rectifier 32 and the D. C. out-

put is connected by means of the leads 33 and 34 to terminals 1 and 2 of the female cable connector 35.

The transformer 23 provides the voltages for the operation of the amplifier 20 and includes in this embodiment three separate secondary windings 36, 37 and 38. The winding 36 is a high voltage secondary and has its outer terminals connected to the plates 39 and 40 of a full wave rectifier 41. The filament 42 of the rectifier 41 is heated by the secondary winding 37. This arrangement provides for full wave rectification with the positive lead 43 of the voltage supply being connected to the filament and the negative lead 44 being connected to the center tap of the winding 36. The voltage developed between the conductors 43 and 44 is filtered by a pair of condensers 45 and 46 and an intervening series connected filter choke 47. The output voltage appearing across the condenser 46 is stabilized by means of a resistor 48 in series with the positive conductor 43' and a voltage regulator 49 bridging the conductor 50 connected to the output of resistor 48 and the negative conductor 44. This filtered voltage is now applied to the female connector 35 with the lead 50 being connected to terminal 5 of that connector and the lead 44 to terminals 3 and 7 as illustrated.

The third winding 38 of the transformer 23 provides the filament voltage for the tubes within the amplifier 20 and in addition a rectified bias voltage. More specifically, the terminals of the winding 38 are connected by means of the leads 51 and 52 to the female plug 35 with the lead 51 being connected to terminal 6 thereof and the lead 52 being interconnected with the lead 44 and consequently terminals 3 and 7. If desired the lead 44 may be connected directly to ground. The negative bias voltage is produced by a pair of rectifiers 53 and 54 connected as a voltage doubler, a pair of condensers 55 and 56 and a load resistor 57. This produces a voltage of the order of 15 volts on the output lead 58 which is connected to terminal 4 of the connector 35.

As previously discussed the invention provides means for the selective operation of a plurality of motors or other electromechanical apparatus. To attain this end an individual amplifier 20 may be employed for each motor or in the alternative additional amplifiers 20 omitting the initial stage of amplification may be interconnected with the first amplifier at a point after the first stage of amplification as illustrated in the figure. Considering the illustrated embodiment of the invention the microphone 15 is connected by means of the cable 16 and a plug 60 to an input jack 61. The microphone 15 is preferably of the carbon button type and is connected by means of said jack between the cathode 61' of the first amplifier tube 62 and the ground conductor 63. The resistance of the microphone provides the bias for the tube 62 and its grid 63 is therefore connected directly to ground. The plate circuit of the plate 65 includes a series resistor 66 and the conductor 67 which connects to terminal 5 of a male cable connector 68. This male connector cooperates with terminal 5 of female connector 35 and in this way high voltage from the conductor 50 of the power supply is applied to the conductor 67 of the amplifier 20. The output of the first stage is taken from its plate 65 through a coupling condenser 69 as illustrated.

As mentioned above the initial stage of amplification just described may either form part of each amplifier 20 used for the selective operation of a number of motors or a single common stage may be employed for all amplifiers. In the latter case the output from the condenser 69 is fed through a series resistor 70 to the grid 71 of a pentode vacuum tube 72. If additional amplifiers 20 are used the condenser would also be connected through a lead 73 to additional series resistors 74 and 75 which correspond in other amplifiers to the resistance 70 of the illustrated amplifier 20.

The tube 72 is connected in a generally conventional manner, with the grid 71 being returned to ground through a resistor 76. The suppressor grid 77 and cathode 78 are connected to ground through a resistor 79 and condenser 80 to provide bias for the grid 71. The screen grid 81 is connected through a resistor 82 and lead 83 to the high voltage conductor 67 and is also bypassed to ground by a condenser 84. The plate 85 is connected to the high voltage conductor 67 through a resistor 86 and the output is taken from the plate 85 through a coupling condenser 87 to conductor 96.

In order to provide frequency selectivity for each amplifier 20 the tube 72 is provided with a feedback circuit including a band rejection filter that will limit the operation of the amplifier to a relatively narrow pass band of about twenty cycles. This is attained by means of a twin T filter connected to conductor 96 and including three condensers 88, 89 and 90 and three resistors 91, 92 and 93. The condensers 88 and 89 are connected in series one with the other and the resistors 91 and 92 are similarly connected. The outer terminals of resistor 91 and condenser 88 are connected to the output side of the coupling condenser 87 while the outer terminals of the condenser 89 and resistor 92 are connected through a coupling condenser 94 and the lead 95 to the grid 71 of the tube 72. This provides a feedback circuit from the plate 85 to the grid 71. The junction between condensers 88 and 89 is connected to the ground conductor 63 through the resistor 93 while the junction between resistors 91 and 92 is connected through condenser 90 to the ground conductor 63. This double T filter functions as a narrow band rejection filter in that the filter has a very high impedance over a narrow selected range of frequencies so that little voltage is fed back to the grid and consequently a relatively large signal appears at the plate 85. At all other frequencies the impedance of the filter is relatively low and presents a large feedback signal to the grid 71 and maintains the signal at the plate 85 at a very low level.

The output signal from the condenser 87 is fed through the conductors 96 and 97 to the grid 98 of the tube 99. The plate 100 of this tube is connected to the conductor 67 while the cathode 104 is connected through a pair of resistors 101 and 102 to the ground conductor 63. The grid 98 is returned through a resistor 103 to the center tap of resistors 101 and 102. The tube 99 in this way functions as a cathode follower amplifier and the output is obtained from the cathode 104 through a coupling condenser 105. The signal appearing at output side of the condenser 105 is an A. C. signal and is transformed into a D. C. signal by its rectifier 106 and resistors 107 and 108. In addition a negative bias is applied by means of terminal 4 of cable connector 68 and lead 108' to the bottom side of resistors 107 and 108. A rectified output signal from the positive side of the rectifier is connected through the conductors 109 and 110 to the grid 111 of tube 112. The cathode 113 is connected directly to ground while the plate 114 is connected through the coil 115 of relay 116 to the positive conductor 67. The bias provided by conductor 108 in effect biases the grid of the tube 112 negatively so that it does not draw current. When a signal is impressed on the condenser 105 it is rectified and upon exceeding the value of the negative bias it will swing the grid 111 positively and cause it to conduct current whereupon the relay coil 115 will be energized to actuate the movable contact 117 of the relay and cause it to touch the fixed contact 118. It will also be observed in this connection that the grid 111 of the tube 112 is provided with a condenser 119 between the grid and conductor 63. This condenser together with the resistor 107 forms an RC network having a time constant that is a function of the values of these components and is preferably made long enough so that when the tube 112 conducts current by reason of the application of a positive voltage or a less negative voltage

to the grid 111 the tube will remain conducting for a predetermined period of time. In this way the operator need not continue the voice signal after he has caused the relay to function. It is also to be observed that the utilization of a negative bias on the grid 111 and the condenser 119 produces a delayed action so that the tone that is sounded for operation of the relay must be sustained for a predetermined length of time before sufficient voltage will be developed to operate the tube 112 and relay 116. In this way sharp sounds such as those obtained by knocking the microphone or produced by normal speech will not function to operate the relay 16. Thus the entire device is immune to random noises or signals and is at all time under the complete and positive control of the operator.

The electromagnetic apparatus 22 operated by the relay 16 includes a drum type reversing switch 120 having ring contacts 121 and 122 on the ends thereof and four elongated contact members 123 spaced at about 90 degrees one from the other with alternate contacts connected to the ring 121 and the intervening contacts to the ring 122. Coupled with the drum switch 120 is a ratchet 124 and pawl 125 for operating the ratchet. The pawl is actuated by an armature 126 in a coil 127. The contact 117 of the relay 116 is connected, in this embodiment of the invention, through a lead 128 to terminal 1 of the male connector 68 which in turn is connected through the connector to the lead 34 of the rectified voltage from transformer 24. The cooperating relay contact 118 is connected through conductors 129 and 130 to the ground lead 63 of the amplifier 20 which in turn is connected to the contact 3 of the male connector 68. The top side of the plunger magnet coil 127 is connected through lead 130' to the junction of leads 129 and 130 while the lower terminal of this coil is connected to the ring 121 of the rotary switch 120 and through a conductor 131 to terminal 2 of the male connector 68. It will be observed that when the relay contacts 117 and 118 are closed voltage will be applied to the plunger magnet 127 which will then actuate the pawl and ratchet to rotate the drum switch 120, 45°.

The armature of motor 132 is connected through commutator brushes 133 and 134 to brushes 135 and 136 which ride on the surface of the drum. These brushes are positioned relative to the elongated terminal members 123 so that as the drum is rotated 45 degrees the brushes 135 and 136 will first contact adjoining terminal members 123 and upon subsequent increments of rotation will rest upon the insulating material between the contacts 123 and then the next successive pairs of members 123 etc. In this way the flow of current through the brushes 133 and 134 will be successively interrupted and reversed. To complete the motor circuit the ring 122 on the drum switch 120 is connected by a conductor 137 to one terminal of the field 138 the motor 132 and other terminal of the field is then connected through a conductor 139 to the lead 130'. Thus the energy for operating of the motor is obtained from the rectified supply of transformer 24 and its operation is completely under control of the drum switch 120.

With the apparatus as described above when the operator sounds a tone in his throat of a selected frequency for a predetermined interval, he will cause the relay 116 in the amplifier 20, responsive to that frequency, to operate and this in turn will cause the motor 132 to be operated in one direction. The motor will continue to operate even after the relay 116 is deenergized. To stop the motor the same signal is given a second time. This functions to close the relay 116 and operate the plunger magnet 126 which through action of the drum switch 120 interrupts the armature circuit of the motor 132. To reverse the operation of the motor he sounds the signal a third time to actuate the relay 116 and plunger magnet 126. This completes the motor armature circuit but in the reverse direction and causes the motor to run in a

direction opposite to that in which it was previously operated.

The motor 132 may be coupled to the operating cables 11 of the prosthetic device 10 in any suitable manner. One system for the attainment of this end includes a speed reducing assembly consisting of a worm gear 140 coupled to the motor 132 and a cooperating gear 141 connected to a spool 142 about which the cables 11 are wrapped. If desired the spool 142 may include a slip clutch to limit the maximum force applied to the spool by the motor 132.

From the above it is apparent that through the utilization of additional amplifiers connected with the resistors 74 and 75 additional electromagnetic units such as unit 22 may be selectively operated. In practice it has been found that in a case wherein three such electromagnetic units 23 are to be employed that frequencies of the order of 220 cycles, 280 cycles and 330 cycles can be reproduced easily and precisely by the operator and permit him to secure selective motor control. In the case where he uses a prosthetic device of the type shown in Figure 1 for each hand two such motor units 22 would be employed and he could operate each hand as desired.

While only one embodiment of the invention has been shown and described it is apparent that transitions and other similar devices may be used to increase portability and that further modifications, alterations and changes may be made without departing from the true scope and spirit thereof.

What is claimed is:

30. 1. An electronic control for prosthetic devices comprising a microphone, an amplifier including a filter for limiting the response of said amplifier to a predetermined frequency range, means for rectifying the output signal of said amplifier, a second amplifier responsive to said rectified output signal, means including a time delay network for negatively biasing said second amplifier, a relay including at least two cooperating contacts and responsive to the last said amplifier, and electromagnetic means operable in response to said relay for actuating said prosthetic device.
35. 2. An electronic control for prosthetic devices according to claim 1 wherein said electromagnetic means includes a motor and an electromagnetically operated reversing switch connected with said relay and said motor.
40. 3. Voice operated apparatus comprising a microphone, an amplifier connected with said microphone a band pass filter for limiting the response of said amplifier to a predetermined frequency band width, means for rectifying the filtered signal, means including a relay actuated by the rectified signal and means in circuit with said rectifier for delaying operation of said relay until the signal is sustained for a predetermined period and for holding said relay in the actuated position for a predetermined interval after removal of said sustained rectified signal.
45. 4. Voice operated apparatus according to claim 3 wherein said filter comprises a vacuum tube connected as an amplifier, a feedback circuit between the input and output of said tube and a band rejection filter in said feedback circuit.
50. 5. In voice operated apparatus, a vacuum tube having a cathode, grid and plate, means for applying a voltage between the plate and cathode of said tube, a carbon microphone connected in series with the cathode of said tube, at least one amplifier responsive to the signal produced by said tube and including a filter for limiting the frequency of the output signal of said amplifier to a predetermined narrow frequency range, a rectifier for rectifying said output signal, a second amplifier including time delay means connected with said rectifier and electromagnetic means responsive to said second amplifier.
55. 6. A voice operated electronic control for prosthetic devices comprising a vacuum tube amplifier having a cathode circuit, a carbon microphone in series with said

cathode circuit, and at least one frequency selective control means coupled with said amplifier including a second vacuum tube amplifier having a frequency selective feedback circuit, means for rectifying the output of said second amplifier, a third amplifier including negatively biased time delay means to delay the response thereof to both positive and negative changes in the rectified signal, a relay connected with the last said amplifier and responsive to the signal produced thereby, a magnetically operated rotary reversing switch actuated by said relay and 10 a reversible motor connected to said switch.
